CHARLES L. MURPHY, OF CINCINNATI, OHIO.

CLOSURE FOR CONTAINERS.

1,420,734.

Specification of Letters Patent. Patented June 27, 1922.

Application filed June 30, 1921. Serial No. 481,538.

To all whom it may concern:

Be it known that I, CHARLES L. MURPHY, a citizen of the United States, residing at Cincinnati, in the county of Hamilton and State of Ohio, have invented certain new and useful Improvements in Closures for Containers, of which the following is a specification.

My invention relates to bottles and jars, and its object is to simplify and economize in the construction and use of such articles; to have them securely closed when required, but readily opened repeatedly. It is the more especial object of my invention to provide these advantages in connection with bottles for medicinal, toilet preparation, chemical, and prescription use, and the like. Other objects will appear in the course of the ensuing description.

I attain these objects by the device illustrated, for example, in the accompanying drawing, in which—

Figure 1 is a plan view of a part of a bottle provided with a closure embodying my invention, in closed condition;

Fig. 2 is a side elevation of the same;

Fig. 3 is a side elevation of the same with the cap removed;

Fig. 4 is a plan view of the same with the cap removed;

Fig. 5 is a vertical cross-section of the same on the plane of the line 5—5 of Fig. 1;

Fig. 6 is a front elevation of the cap;

Fig. 7 is a sectional front elevation of the bottle and the closure, the section being on the vertical plane of the line 7—7 of Fig. 1;

Fig. 8 is a front elevation of the bottle with the cap removed;

Fig. 9 is a similar view with the cap in its initial position on the bottle in the closing operation;

Fig. 10 is a bottom plan view of the cap;

Fig. 11 is a similar view of a modified cap; and

Fig. 12 is a section corresponding to that of Fig. 7, but showing a wide-mouthed bottle or jar provided with a closure embodying my invention.

The bottle which I have chosen for illus-

tration is of the kind known in the trade as 50 prescription finish; although it will be understood that the particular style of the bottle is immaterial, and for that reason only the upper part of the body 1 and the neck 2 are shown in the drawing. The outlet 55 3 of the neck 2, as here shown, is narrow, such as would, as these bottles usually are employed, be closed by a cork or other stopper; which closure, so far as I am aware, is the only kind that has been considered dependable for this kind of bottles, especially for holding readily flowing liquids, volatile or especially thin liquids, and the like, where a tight closure must be maintained. Around the outlet 3 the end of the 60 neck 2 has the cap-seating surface 4; as here shown being in a plane at right angles to the outlet axis, as is common in this type of bottles, although it will be understood that other dispositions of this surface may occur. The essential character of this surface 4 is that it shall have a material extent such that the cap 5, of inverted cup-like formation, may have an interior surface in intimate contact with the surface 4 65 throughout the extent around the outlet 3. As shown, this interior surface of the cap 5 is provided by a disk 6 of suitable packing or gasket material, such as cork, for instance, fitting snugly up in the cap, as is well known 70 in the art.

The container or bottle neck 2 has the diametrically opposite outwardly extended segments 7, each with a bottom shoulder 8 inclining downwardly with respect to the seating surface 4 at a material angle, from one end of the segment to the other, around the bottle or neck 2. Each shoulder 8 preferably also inclines downwardly with respect to said surface 4, radially inwardly of the 85 bottle or neck 2; this being a shape that adds to the convenience of molding a glass container with such a shoulder, as well as contributing to the operation of the closure as will be described. As here shown, the top 90 of each segment 7 is in the same plane as and continuous with the seating surface 4 95 at the top of the bottle. The segments 7

thus related make up a bottle formation which characterizes the bottle as one of prescription finish, as before alluded to; in that there is an ample lip, projected past the 5 lower part of the neck 2 and with its top uninterrupted from the outlet 3, facilitating pouring and dropping liquids from the bottle, as is especially desirable for medicinal use. Also, with these continuous plane 10 topped segments, the cap 5 is supported out closer to the line of strain of closing pressure. Also, as shown, each segment has its deeper end abrupt, as at 9; but the other end is gradually reduced in radial extent, 15 eccentric to the neck and outlet, as at 10, discontinuing entirely some distance from the abrupt end 9 of the other segment, leaving a space 11 between the segments 7, normal to the neck surface. This affords a 20 better entrance to the shoulders 8. However, it will be understood that these details may be varied from, under different conditions.

Diametrically opposite to each other on 25 the cap 5, depending from the rim of the inverted-cup formation of the cap, are the lugs 12, each with a radially inner upwardly facing shoulder 13 at its bottom. Each shoulder 13 has its upper surface inclined 30 downward from the cap seating surface on the disk 6, around the cap, from one end of the lug 12 to the other. The cap 5 is placed on the bottle as shown in Fig. 9, by bringing the lugs 12 down along the spaces 11 and the 35 adjacent eccentric parts 10; the radially inward extension of the shoulders 13 being limited to pass the adjacent moderately extended parts 10. The inclination of these parts 10 around to the adjacent spaces 11 40 readily guides the lugs to their correct initial positions against the abrupt ends 9. The inclination of each shoulder 13 corresponds to that of each downwardly facing shoulder 8 of the neck, with respect to the seating surface 4, around the neck 2. Also, preferably, 45 where the segment shoulders 8 incline radially, as before described, these shoulders 13 also are inclined down, relatively to the seating surface 4, radially to correspond with the 50 inclinations of the shoulders 8. The inner diameter of the cap 5 is such that these lugs 12 will closely flank the segments 7 when the cap is turned on the neck to carry its lugs away from the abrupt segment ends 9; and 55 the up-and-down dimensions of the lugs 12 are such that as this turning progresses, the lug shoulders 13 ride snugly along the segment shoulders 8. As here shown, each shoulder 13 inclines in the described way 60 throughout its extent around the device, so that it has a relatively very extensive bearing surface on the neck segment shoulder 8 to which it is applied. Also, as here shown, each segment shoulder 8 is inclined in the 65 described way throughout its length. Such

inclination of the shoulders 8 and 11 throughout their lengths is preferable; being simple formations and affording the maximum bearing surfaces which it is one of the objects of my invention to provide. It will 70 be understood that if any of the extent of either the cap lug 12 or the neck segment 7 be varied, so that such shoulders, of the described inclination, are not present throughout the extent of the part, the requirements 75 of my invention are met if a material extent of the cooperating shoulders on neck and cap are so correspondingly inclined, in a single direction around the device. Such an extended bearing surface affords the 80 security required, according to my invention; dispensing with special locking means or the like, as well as with stops and the like, as will be described.

Preferably, the cap 5 is polygonal; that 85 is, its rim is made up of a number of flat sides. As shown in Figs. 1 to 10, it is octagonal; in Fig. 11, hexagonal. Any more or less than six or eight sides may be provided. Such a number of flat sides, with the 90 resulting angles 14, affords a very convenient gripping means for the hand in turning the cap, either in applying it to the container or taking it therefrom. I prefer a moderate number of sides, as six or eight, because of 95 the distinctness of the angles due to relatively wide spacing and affording a better grip than a large number of small projections, such as corrugations that have been provided on bottle caps and the like. 100

Moreover, I prefer to provide such angles coincident with the lugs 12, from which and from the adjacent sides the lugs taper slightly inward to the curves which the lug shoulders 13 have; the latter preferably being on arcs, substantially, of a circle inscribed in the polygon of the cup rim (Fig. 6, 10 or 11.) This braces the lugs 12 against springing outwardly; especially when the radial inclination of the shoulders 8 and 13 110 is provided, as before described, this bracing is desirable. Whether the cap be polygonal or not, such a provision of reinforcing angles at the lugs 12 is desirable for these reasons. Also, to strengthen the lugs 12, a fillet 15 is 115 provided at one end where the shoulder 13 is highest, and a fillet 16 is provided at the other end, of each lug 12 where it joins the main part of the cap rim; the latter fillet 16 being of ample radius, but the fillet 15 being 120 smaller to make room for coming down past the abrupt end 9 of the neck segment in first placing the cap on the bottle. As before stated, the cap shoulders 13 are not of excessive radial inward extent. They are wide 125 enough to afford ample bearing along the neck shoulders 8, in their conformity thereto as before described; but clear the main part of the neck, at the neck and shoulder junction, to an ample extent. In general, 130

these and the other parts of the bottle and cap are so proportioned that the necessary bearing parts will fit together snugly, with ample frictional holding effect, but other parts, with which such snug fitting is not needed, are spaced sufficiently to avoid hindrance if either the cap, or the bottle, especially the latter, should be slightly inaccurately formed. The lugs 13 wedge on the lugs 8 radially with added effect.

In Fig. 12, the cap and bottle or jar formations will be understood to be substantially as in the preceding examples. The jar has the body 1' with neck 2' and wide mouth 3' surrounded by the seating surface 4' for the cap 5'. The cap has the disk 6' to bear on the surface 4', represented as relatively thinner; such containers usually being for dry or viscid substances, and the disk 6' being of paper or the like. The segments 7' with their shoulders 8' receive the shoulders 13' of the cap lugs 12'; the only notable differences being those of proportion, due to the greater diameter of the neck 25 and cap relative to the depth of the neck segments 7' and the cap lugs 12', which varies the inclination of the shoulders 8' and 13', around the jar, somewhat from that on the smaller bottle neck. The depth of the segments and lugs may vary proportionately if desired, giving the same inclination.

The cap 5 being placed on the bottle neck 2 as shown in Fig. 9, with the lugs 12 and their shoulders 13 guided down into the spaces 11 by the abrupt ends 9, against which they are guided by the inclined ends 10 of opposite segments 7, is turned around to the right, according to the disposition of parts herein shown. At some period 40 of this turning, the shoulders 13 of the cap begin to engage with the shoulders 8 of the container, wedging thereon with correspondingly inclined surfaces. The turning is continued until the tightness, judged by the resistance, is sufficient; this increase in tightness being possible throughout the travel of the cap shoulders 13 along the neck shoulders 12. Preferably the parts are so proportioned that when the lowest part of the shoulder 13 coincides with the far end 9 of the segment 7, the maximum required tightness has been provided. More or less tightness of closure is desirable, depending upon the nature of the contents, or ease or frequency of opening required. For original packing of proprietary articles, full tightness may be used. The consumer, at repeated openings and closings, may not close the container so tightly. For prescriptions, 60 the tightness may be varied for the convenience of the consumer. In practice I find that with moderate tightness, the described closure remains closed and sealed, and is not displaced or opened by transportation and handling. Even with extreme tightness of

closure, the removal of the cap, which is done by twisting back in the opposite direction to that of closure, is accomplished with ease to the user. Such easy opening is especially desirable in containers for sticky substances and the like, in which stoppers or more complex closures are difficult to remove after standing some time after the contents have contacted with the closure parts at a previous withdrawal from the container. 75 Notwithstanding such ease of opening, the closure as described is found in practice to retain thin liquids, or the volatile substances, as efficiently as they are retained by corks and the like used as stoppers; and to resist 80 opening, even by impacts against the angular rim of the cap.

Such a cap is advantageously made of sheet metal, as sheet steel, preferably enameled exteriorly, and provided with suitable 85 packing 6 interiorly as with numerous other kinds of caps. The caps may be made with their lugs 12 straight up and down, without the shoulders 13, and then be applied to the bottles or other containers and these lugs 90 formed inward to form the shoulders under the neck segments; either with maximum tightness, or partially tight, to be fully tightened by a slight twist. Such operations can be performed by a special machine, for 95 bottling or packing in large quantities, as with proprietary articles. Or the caps may be furnished in their complete condition, to be put on as before described, either by hand or by special mechanical means. This 100 method can be used for large quantities, or more particularly for moderate quantities, or by druggists, in prescription or other bottling or packing. The simple bottle or container design permits the bottles or 105 containers to be made of glass without difficulty, involving no problems of intricate or impracticable molds. The containers so formed are substantial, without disproportionate projections or sharp breaking recesses or 110 angles.

Modifications others than or in addition to those instanced herein may occur; and while certain constructional details are deemed preferable in connection with my invention, 115 and I have shown and described these rather specifically in elucidating the construction and use of my invention, as is required, I do not wish to be understood as being limited to such precise showing and description, but 120 having thus fully described my invention, what I claim as new and desire to secure by Letters Patent is:

1. A container having an outlet with a cap-seating surface therearound, and shoulders facing away from said surface at intervals around the container, and a cap seating on said surface, with shoulders at intervals therearound to engage with respective ones of said container shoulders, said cap shoul- 130

ders and corresponding ones of said container shoulders being, in their extent around the container, substantially correspondingly of increasing distance from said seating surface, measured on a line perpendicular to said surface, in one direction only around the container.

2. A container having an outlet with a cap-seating surface therearound, and shoulders facing away from said surface at intervals around the container, and a cap seating on said surface, with shoulders at intervals therearound to engage with respective ones of said container shoulders, said cap shoulders and corresponding ones of said container shoulders being, in their extent around the container, substantially correspondingly of increasing distance from said seating surface, measured on a line perpendicular to said surface, throughout the extent of the respective cap shoulders.

3. A container having an outlet with a cap-seating surface therearound, and shoulders facing away from said surface at intervals around the container, and a cap seating on said surface, with shoulders at intervals therearound to engage with respective ones of said container shoulders, said cap shoulders and corresponding ones of said container shoulders being, in their extent around the container, substantially correspondingly of increasing distance from to said seating surface, measured on a line perpendicular to said surface, around the container and away from said surface radially inwardly of the container.

4. A container having an outlet with a cap-seating surface therearound, and shoulders facing away from said surface at intervals around the container, and a cap seating on said surface, with shoulders at intervals therearound to engage with respective ones of said container shoulders, and having angles formed in its rim within the limits of the respective shoulders, with parts tapering radially inwardly from said angles to the respective shoulders, reinforcing the cap against the stresses due to the shoulder engagement, said container shoulders and said cap shoulders being substantially correspondingly inclined to said seating surface.

5. A container having an outlet with a cap-seating surface therearound, and shoulders facing away from said surface at intervals around the container, and a polygonal cap seating on said surface, with shoulders at intervals therearound to engage with respective ones of said container shoulders, said container shoulders and said cap shoulders being, in their extent around the container, substantially correspondingly of increasing distance from said seating surface, measured on a line perpendicular to said surface, and each one of said cap shoulders having a respective angle of the polygonal cap

within the angle of its extent around the cap, to transmit the strain on said shoulder to other parts of the cap.

6. A container having an outlet with a cap-seating surface therearound, and shoulders facing away from said surface at intervals around the container, and a polygonal cap seating on said surface, with shoulders at intervals therearound to engage with respective ones of said container shoulders, each one of said cap shoulders having a respective angle of the polygonal cap within the angle of its extent around the cap, to transmit the strain on said shoulder to other parts of the cap.

7. A container having an outlet with a cap-seating surface therearound, and having lugs on its sides with tops in the plane of said surface, the bottoms of said lugs forming shoulders facing away from said surface at intervals around the container, and a cap seating on said surface, with shoulders at intervals therearound to engage with respective ones of said container shoulders, each one of said container shoulders being, in its extent around the container, of increasing distance from said seating surface, measured on a line perpendicular to said surface, continuously in one direction throughout its extent around the container, and said cap shoulders being inclined substantially correspondingly to the respective container shoulders.

8. A container having an outlet with a cap-seating surface therearound, and having lugs on its sides with tops in the plane of said surface, the bottoms of said lugs forming shoulders facing away from said surface at intervals around the container, and a cap seating on said surface, with shoulders at intervals therearound to engage with respective ones of said container shoulders, each one of said container shoulders being, in its extent around the container, of increasing distance from said seating surface, measured on a line perpendicular to said surface, continuously in one direction throughout its extent around the container, and said cap shoulders being inclined substantially correspondingly to the respective container shoulders throughout the extent of said cap shoulders.

9. A container-closing cap of polygonal shape with lugs on its rim at intervals therearound coincident with respective angles of the polygon, and shoulders on the respective lugs extended inwardly across the main body of the cap, following substantially arcs of a circle inscribed in the polygon, said lugs inclining from their respective polygonal angles to their respective shoulders.

10. A container-closing cap with lugs on its rim at intervals therearound, said cap having angles in its rim coincident with respective lugs, and shoulders on the respec-

tive lugs following substantially arcs of a circle concentric to the main body of the cap, said lugs inclining from their respective angles to their respective shoulders.

5 11. A container-closing cap with lugs on its rim at intervals therearound, said cap having angles in its rim coincident with respective lugs, and shoulders on the respec-

tive lugs inclined inwardly across and away from the main body of the cap and following substantially arcs of a circle concentric to the main body of the cap, said lugs inclining from their respective angles to their respective shoulders. 10

CHARLES L. MURPHY.
